UNITED STATES PATENT OFFICE.

RICHARD T. GRIFFITHS, OF AKRON, OHIO, ASSIGNOR TO THE MILLER RUBBER COMPANY, OF AKRON, OHIO, A CORPORATION OF OHIO.

LOUD-SPEAKER PANEL.

Application filed April 8, 1925. Serial No. 21,646.

My present invention relates to improvements in panels for use in cabinets of the sound producing type, such for example as a cabinet that is used for radio purposes, 5 and the invention aims to provide a panel which may be built into or used for such cabinets, and which panel will have incorporated therein a sound amplifier or horn, thus enabling the separate and unsightly 10 horns which are now used for loud speaker purposes, to be dispensed with.

The invention comprises the novel construction hereinafter described and defined by the appended claims.

15 An embodiment of my invention is illustrated in the accompanying drawings, in which:—

Figure 1 is a plan view of one face of the panel member.

20 Fig. 2 is an edge view.

Figs. 3 and 4 are sectional views on lines 3—3 and 4—4 respectively of Fig. 1.

25 Fig. 5 is a plan or face view of the covering plate which carries the loud speaker unit and horn bell.

Fig. 6 is an edge view of the plate of Fig. 5.

30 Fig. 7 is a sectional view showing the panel construction embodied in a cabinet as the back wall thereof.

Fig. 8 is a similar view showing how the panel may be incorporated in an ordinary cabinet, and

Fig. 9 is a detail view.

35 Referring by reference characters to these drawings, the numeral 1 designates a panel member or plate of molded material suitable for cabinet work, as for instance, vulcanized hard rubber composition, which

40 plate, of course, may be of any desired size and dimensions. In the molding of this plate, I form it with an elongated and tapered channel or recess indicated at 1^a, the walls of the recess being preferably substan-

45 tially of the same thickness throughout, and being conveniently, and as shown, of the same thickness as the plate itself, and of course, being integral therewith. This recess forms the sound amplifying chamber, and in

50 order to get the desired length in a medium sized panel, I make the channel in the shape of a reverse curve as shown, thus provid-

55 ing two substantially parallel channel portions. The small end of the channel is rounded to merge with the plate and form a

closed end for the channel, as indicated at 1^b, and the larger end is similarly rounded and closed, as indicated at 1^c. The channel, if desired, may be provided with projecting flange portions 1^d extending entirely around 60 the sides and ends of the channels on the opposite face of the plate or panel, thus making the channel deeper than would otherwise be the case, and the flange serving to stiffen the plate or panel member. Cooperating with the channel member thus described is a closure member shown in plan view in Fig. 5, which preferably has an outline of substantially the same outline as the channel, but slightly larger so as to rest 70 against the flanges 1^d and completely close the channel with the exception of the small and large ends thereof, which are left open by reason of the circular openings 2^a and 2^b formed in the plate 2. The portions of the 75 plate carrying these openings 2^a and 2^b are preferably thickened or provided with flanges *a* and *b* respectively, which are adapted to receive, the former the ordinary loud speaker unit (shown conventionally at 80 3), and the latter, a bell mouth, indicated at 4. The connection of these parts may be made either by a threaded connection or a slip joint, or otherwise, as desired. The plate 2 is preferably provided with openings 85 *e*, which may be formed in ears or projections 2^c, which openings are adapted to receive screws for fastening the closure member to the channel member, such screws entering openings *e* tapped in the lugs 1^e 90 formed on the plate 1 adjacent the edges of the channel. The panel member may be provided at its edges with grooves 1^f for forming a tongue and groove connection with the end walls of the cabinet, and with top and 95 bottom edge flanges 1^g to enter corresponding grooves in the top and bottom of the cabinet, as shown in Fig. 7. The front of the cabinet may consist of the ordinary grill work 5.

100 However, the device may be placed as a unitary article in the back of an ordinary cabinet instead of being used to form the rear panel or back wall of the cabinet, in which event the panel member 1^x and plate 105 2^x would form a supplemental back or spaced member.

Before assembling the two panel members, it is desirable to coat the adjoining edges with an adhesive cement such as rubber ce- 110

ment, whereby an air tight connection is secured.

Having thus described my invention, what I claim is:—

- 5 1. In combination, a panel member of molded material having a tapered cavity therein, and a closure member therefor having circular openings corresponding to the larger and smaller ends of said cavity.
  - 10 2. A panel member of molded material having a tapered cavity therein, and a closure member therefor having circular openings corresponding to the larger and smaller ends of said cavity, said smaller opening
  - 15 having means for connecting a loud speaker unit.
  - 20 3. A panel member of molded material having a tapered cavity therein, and a closure member therefor having circular openings corresponding to the larger and smaller ends of said cavity, and a bell mouth element connected with said larger unit.
  - 25 4. A panel member of molded material having a flaring channel therein provided with portions disposed substantially parallel
- to each other with the walls of the panel member and channel portion of equal thickness throughout, and a closure member for the channel of substantially the same thickness, said closure member having large and small 30 openings coinciding with the respective ends of the channel.
5. A panel member having an elongated tapered channel therein provided with rounded end walls, and a closure member 35 covering the channel and provided with circular openings coinciding with the ends of the channel and conforming thereto in size.
6. A panel member for the back wall of a radio cabinet composed of hard rubber having a flaring channel formed therein and disposed lengthwise thereof, said channel having rounded ends, a closure member for said channel having openings coinciding with the ends of said channel, said closure member 40 45 having annular flanges encircling the openings therein for attachment of a loud speaker unit and bell member.

In testimony whereof, I affix my signature.
RICHARD T. GRIFFITHS.
